Primary Examiner — Mary Ann Calabrese(74) *Attorney, Agent, or Firm* — Panitch Schwarze Belisario & Nadel LLP(57) **CLAIM**

The ornamental design for an electronic luggage tag, as shown and described.

DESCRIPTION

FIG. 1 is a front elevation view of a first embodiment electronic luggage tag in accordance with my new design;

FIG. 2 is a top plan view thereof;

FIG. 3 is a bottom plan view thereof;

FIG. 4 is a rear elevation view thereof; and,

FIG. 5 is an elevation view of the left side thereof, the right side being a mirror image.

The broken lines in the figures identify portions of the electronic luggage tag that form no part of the claimed design.
